CLAIM

I claim the ornamental design for the CPAP face mask, as shown and described.

DESCRIPTION

FIG. 1 is a front view of the CPAP face mask;
FIG. 2 is a top view thereof;
FIG. 3 is a bottom view thereof;
FIG. 4 is a left side elevational view thereof taken from FIG. 1;
FIG. 5 is a right side elevational view thereof taken from FIG. 1;
FIG. 6 is a rear view thereof; and,
FIG. 7 is a perspective view thereof.
